UNITED STATES PATENT OFFICE.

PERCY M. WARDELL, OF DUNMORE, PENNSYLVANIA.

SPINDLE LOCK.

Application filed December 31, 1921. Serial No. 526,166.

To all whom it may concern:

Be it known that I, PERCY M. WARDELL, a citizen of the United States, residing at Dunmore, in the county of Lackawanna 5 and State of Pennsylvania, have invented certain new and useful Improvements in Spindle Locks, of which the following is a specification.

This invention relates to spinning machines, and the primary object of the invention is to provide a novel retainer or lock for preventing the accidental displacement of the spindle from the bolster or support when the bobbin is being removed there- 15 from.

Another object of the invention is to provide a novel retainer or lock which can be readily and quickly associated with a spindle of any approved type, and which will 20 permit the spindle to be easily removed when desired and which is not liable to become broken by rough usage.

A further object of the invention is to provide a novel retainer or lock for spindles 25 which can be placed at any desired adjusted point on the spindle so that the same can be readily manipulated when desired, and so that the same will be out of the way of other parts of the spinning machine, and 30 which is held in place by ordinary parts of the spinning machine and which will tend to reduce vibration between the spindle, bolster and the supports or casting for the bolster.

A still further object of the invention is 35 to provide an improved lock or retainer for spindles of spinning machines of the above character, which will be durable and efficient in use, one that will be simple and easy to manufacture, and one which can be placed upon the market at a reasonable 40 cost.

With these and other objects in view, the invention consists in the novel construction, 45 arrangement and formation of parts, as will be hereinafter more specifically described, claimed and illustrated in the accompanying drawings, forming a part of this specification, in which drawings:

50 Figure 1 is an elevation of a spindle and the supporting structure, showing the novel retainer or lock associated therewith.

Figure 2 is a plan view of a spindle and its supporting structure showing the im- 55 proved retainer or lock associated therewith.

Figure 3 is a plan view of a novel lock

or retainer showing the same applied to a spindle and supporting structure, the spindle being shown in cross section.

Referring to the drawings in detail, 60 wherein similar reference characters designate corresponding parts throughout the several views, the letter A indicates a spindle, which is associated or journaled in the bolster B in the ordinary manner.

The bolster B normally rests upon the supporting bracket C, which is provided with a central aperture (not shown) for the reception of the depending stud D formed on the bolster. The lower end of 70 the stud D adjustably carries the nut E and between the upper face of the nut and the under side of the support C is confined a spring F, which normally tends to draw the bolster B down into engagement with 75 the supporting bracket C.

The supporting bracket C is provided with an upwardly extending pin G, which normally fits in a notch H formed in the bolster.

The spindle A has mounted upon the same in the usual manner a pulley I, the lower end of which is provided with an out-standing flange K.

The above described parts are of the ordinary construction and the improved lock L is adapted to be associated therewith without making any change in the formation thereof for retaining the spindle A against displacement.

The improved retainer or lock L includes a disc shaped plate 5, which is provided with an axial opening 6, for the reception of the spindle A. This plate 5 is positioned between the supporting bracket C and the bolster B and if desired, felt washers 7 may be placed upon the opposite sides of the plate and in engagement with the bracket structure C and the bolster B. These washers will tend to reduce vibration. An up-standing arm 8 is formed on the periphery of the disc 5 and this arm can have its upper end provided with a right angularly disposed radially extending leg 10. The leg 10 may in turn terminate in a depend- 105 ing lug 11, which is disposed in parallelism to the arm 8.

The plate 5, the arm 8, the leg 10 and the ear 11, can all be stamped from a single piece of sheet metal of the desired gauge 110 if so desired, and the arm 8, the leg 10 and the ear 11 then bent to the desired shape, as

shown in the drawing. Of course, this is purely optional and the device can be cast if so desired. The arm 8 and the ear 11 are provided with registering openings for slidably receiving a locking or retaining bolt 12. This bolt 12 has coiled around the same an expansion spring 13, which normally engages the inner face of the ear 11 and against a collar 14, which may be secured directly 10 to the bolt. This spring normally urges the bolt 12 in the path of the collar K formed upon the pulley I and thus effectively prevents accidental displacement of the spindle A from the bolster B. In order 15 to limit the inward movement of the bolt 12 under the influence of the spring 13 and to permit the ready operation of the bolt when it is desired to remove a bobbin for any reason, the outer end of the bolt 12 is 20 provided with a pull ring 15. This ring 15 normally engages the ear 11 and it is apparent that this ring may be readily engaged by the finger of the operator of the spinning machine for pulling the bolt 12 rearwardly against the tension of the spring 13.

In order to prevent accidental rotation of the plate 5 on the spindle and in order to hold the locking device in any preferred adjusted position on the spindle so that the 30 same can be held out of the way of other parts of the machine, the periphery of the disc 5 is provided at spaced points with locking notches 16, any one of which is adapted to receive the pin G formed upon the supporting bracket C. In applying the 35 disc 5 to the spindle, the pin G is placed in the desired notch 16 and thus it can be seen that movement of the disc around the spindle will be prevented.

Now, when a bobbin is being removed 40 from the spindle A, all likelihood of the spindle being displaced from the bolster is precluded by the bolt 12 engaging in the collar or flange K, and when it is desired 45 to remove the spindle for any reason, it is merely necessary to pull the bolt 12 outwardly, out of the path of the collar.

From the foregoing description, it can 50 be seen that an exceptionally simple and durable lock or retainer has been provided for the spindles of spinning machines, and which is of an inexpensive character, and which can be readily applied to the ordinary type of spindles now on the market.

Changes in details may be made without 55 departing from the spirit or scope of this invention; but,

I claim:

1. The combination of a spindle, a bolster 60 upon which the said spindle is journaled, a supporting member for said spindle, and a retaining device for said spindle including a frame held in place between said bolster and supporting member, and a bolt 65 slidably carried by said frame for engag-

ing the spindle to prevent displacement thereof.

2. The combination of a spindle, a bolster upon which said spindle is journaled, a supporting member for said bolster, a retaining and locking device for the spindle including a supporting frame secured between the bolster and supporting member, a locking bolt slidably carried by said supporting frame for holding the spindle 75 against movement in one direction, spring means normally urging the bolt toward said spindle, and a handle formed on said bolt for permitting the convenient operation thereof.

3. The combination of a spindle, a bolster upon which said spindle is journaled, a supporting member for said bolster, a retaining and locking device for holding the spindle in position including a frame 85 confined between the bolster and the supporting member, means for holding the frame in an adjusted position on said spindle, said frame including a supporting disc and an arm, and a sliding bolt carried by the arm 90 for movement toward and away from said spindle.

4. The combination of a spindle, a bolster upon which the spindle is journaled, a supporting member for said bolster, a retaining and locking device for the spindle including a frame, the frame having a supporting disc mounted upon the spindle for movement around the same, means for holding the plate in an adjusted position on the spindle, and upwardly extending arm formed on the plate, an ear disposed in parallel relation to the arm, a locking bolt 100 slidably carried by the arm and ear, spring means normally urging the bolt toward the spindle, and means for permitting the bolt to be moved away from the spindle.

5. The combination of a spindle, a bolster upon which said spindle is journaled, a pulley carried by the spindle having a 110 flange formed thereon, a retaining device for the spindle including a disc shaped plate disposed between the bolster and supporting member therefor and arranged for movement about said spindle, means for holding the plate against movement in an adjusted position, and a sliding bolt carried by the frame for movement into and out of the path of said flange.

6. The combination with a spindle, a bolster upon which said spindle is journaled, a supporting member for the bolster having an upstanding pin carried thereby, a retaining member for the spindle comprising a frame including a disc shaped plate 125 disposed between the bolster and the supporting member having a plurality of notches formed in the periphery thereof any one of which is adapted to receive said pin, and a sliding bolt carried by the frame 130

for movement toward and away from the spindle.

7. The combination with a vertical spindle, a bolster upon which the spindle is journaled, a supporting member for the spindle, a retaining member for the spindle comprising a frame including a disc shaped plate disposed between the bolster and the supporting member, washers arranged between 10 the plates and the bolster and supporting member, the supporting member having an upstanding pin formed thereon, the bolster having a notch arranged to receive said pin, the plate having a plurality of notches 15 formed in the periphery thereof any one of which is adapted to receive said pin, and a bolt slidably carried by the frame for movement toward and away from said spindle.

8. As a new article of manufacture, a retainer for the spindles of spinning machines comprising a frame including a disc shaped plate, an upstanding arm formed on the periphery of the plate, an outwardly extending leg formed on the arm, a depending ear formed on the leg disposed in spaced 25 parallel relation to the arm, a bolt slidably supported by the leg and arm, an expansion spring coiled around said bolt and confined between the ear and arm for normally urging the bolt in the one direction, and a finger piece carried by the bolt. 30
